CLAIM

The ornamental design for a display screen with a graphical user interface, as shown and described.

DESCRIPTION

The FIGURE is a front view of a display screen with a graphical user interface, showing my new design.

The outermost broken line illustrates a display screen that forms no part of the claimed design. The broken line showings of the display screen, and various features of the graphical user interface are included for the purpose of illustrating environmental structure and portions of the article. The broken lines form no part of the claimed design.
